JAMES M. WADSWORTH, OF FORT WORTH, TEXAS, ASSIGNOR TO PIERCE PETROLEUM CORPORATION, OF NEW YORK, N. Y., A CORPORATION OF DELAWARE.

METHOD AND APPARATUS FOR DISTILLING OIL.

Application filed December 27, 1921. Serial No. 525,179.

To all whom it may concern:

Be it known that I, JAMES M. WADSWORTH, a citizen of the United States, residing at Fort Worth, Texas, have invented a certain new and useful Improvement in Methods and Apparatus for Distilling Oil, of which the following is a full, clear, and exact description, such as will enable others skilled in the art to which it appertains to make and use the same.

This invention relates to the distillation of oil, and particularly crude oil.

It has for one of its objects to provide a highly efficient and practicable method and apparatus for removing the lighter constituents of crude oil of the kind known commercially as "Kansas crude" and dividing said lighter constituents into a series of distillates, each of which has a boiling point range within the limits fixed by commercial requirements.

Another object is to provide a method and apparatus for distilling oil that effect a great saving in the quantity of fuel required to distil crude oil, and make it possible to distil oil without superheating the oil vapors or subjecting the oil vapors to an injurious cracking operation.

To this end I have devised a method of distilling oil, which differs from prior methods in that it contemplates secondary distillation in combination with primary distillation and automatic classification of the condensate on secondary distillation. Briefly described, my method consists in intermittently heating oil that is confined or maintained under a slight pressure, usually about 40 pounds, so as to retard the vaporization of the oil, releasing the oil from confinement or relieving the oil from pressure between the heating operations and subjecting the oil to such treatment as to cause it to vaporize in accordance with the temperatures imparted to it by the heating operations, condensing the vapors evolved in the first heating operation and dividing said vapors in accordance with their boiling points, separately condensing a portion of the vapors evolved during the second heating operation, and subsequently combining the uncondensed portion of the vapors evolved

during the second heating operation with the vapors evolved during the first heating operation. By treating the oil in this manner, namely, heating it intermittently, removing the vapors intermediate the heating operations, condensing a portion of the vapors given off after each successive heating operation separately from the vapors given off after the preceding heating operation, and then combining the uncondensed portion of the vapors with the vapors given off after the preceding heating operation, I eliminate the possibility of the oil becoming superheated or cracked to an appreciable degree and I make it possible to group together in a single distilling operation constituents of the oil which are of like character.

Preferably, the separately condensed primary distillates are re-distilled or re-run in separate bodies and the residue from the bodies of lighter distillates are advanced in series to the bodies of heavier distillates. I also prefer to scrub the vapors leaving the bodies of distillates by a controlled quantity of fresh primary distillates, so as to cause only the vapors of definite gravity to pass from the bodies of distillate, thereby enabling the oil to be classified so precisely as to boiling points as to overcome the necessity of further distilling the oil. In order to economize on the fuel used to heat the oil, I cause the vapors evolved in the primary distillation to be condensed by an exchange of heat between said vapors and the incoming crude oil that is supplied to the apparatus, and I also use the heat in the residue from the primary distillation to heat or re-distill the condensed distillates. In distilling oil according to my method the incoming oil passes through a series of vapor heat exchangers, thence to a series of heating elements. Each heating element gives off a certain amount of vapor in a vapor separating tower provided for the removal of this vapor from the hot oil. The several vapors thus removed pass through the series of vapor heat exchangers, entering the series at different points. In this manner any light vapor given off, for instance, at the third heating element, would have an opportunity of passing through the vapor

heat exchangers uncondensed until it reached a vapor heat exchanger of the proper temperature for condensation, or until it reached a group of vapors of similar boiling point. This same reaction would occur with each vapor fraction; the vapor fraction passing through a certain number of heat exchangers until it reaches a group of similar boiling point fractions where it will be condensed; this grouping of similar boiling point fractions being accomplished by the difference in temperature of each vapor heat exchanger, which, in turn, is controlled by the flow of the incoming crude oil from the first vapor heat exchanger to the second, etc. In the vapor heat exchanger the similar boiling point fractions, as rapidly as condensed, flow through another type of heat exchanger which is mounted upon the secondary distilling apparatus, several of these secondary distilling apparatus being provided, which apparatus are connected up in series.

The same feature of distillation is employed in the secondary apparatus as the similar boiling point fractions are charged through the several exchangers on top of each secondary distilling apparatus and the residue from the primary distilling apparatus, not entirely evaporated by its temperature, flows into the next distilling apparatus, etc., in this manner being automatically classified according to boiling point. The result is that a number of close boiling fractions are evaporated and kept separate. In my method and apparatus, by means of taking advantage of the fractionating heating and fractionating cooling oil and vapor, I secure the effect of a number of distillations, in that as the oil is passed through the apparatus it is constantly being classified and grouped into similar boiling fractions until at the completion of the process these vapors have been so closely grouped as to be commercial fractions suitable for the market.

While various forms of apparatus may be used to practice my method, I prefer to use an apparatus that comprises a plurality of pipe coils for initially heating the oil, a group of vapor separators through which the oil is passed between the separate heating operations and equipped with baffles that effect the separation of the vapors from the liquid oil, fractional oil condensers or heat exchangers in which the vapors are fractionally condensed by interchange of heat between the vapors and the incoming crude oil, means for causing the vapors given off after each heating operation to pass through heat exchangers separate from those through which vapors pass from the preceding heating operation and then through said last mentioned heat exchangers, re-run stills through which the condensed

distillates are passed continuously and in which said distillates are heated in the presence of steam by the residuum from the primary distillation, connections between the re-run stills that permit the residuum from the still containing the lighter distillates to be conducted to the stills containing the heavier distillates and the residuum from the primary distillation to be passed through heating tubes in the re-run stills in a direction opposite to the flow of the distillate through the re-run stills, and crock towers on the re-run stills into which the distillate may be discharged directly from the fractional oil condensers, said crock towers being so constructed that the gravity of the vapors evolved in the re-run stills can be accurately controlled. A primary still is combined with the pipe coils in such a manner that oil which passes through the pipe coils and vapor separators without being vaporized may be heated in said primary still in the presence of steam, and if desired, means may be provided for permitting vapors from the primary still to be introduced into the last vapor separator of the group and subjected to a scrubbing action in said separator. While I have herein described and illustrated my invention embodied in a topping plant for crude oil, I wish it to be understood that my method and apparatus are not limited to the distillation of crude oil or to the removal of only the lighter constituents of crude oil.

Figure 1 of the drawings is a diagrammatic view of a topping plant constructed in accordance with my invention.

Figure 2 is an elevational view of a portion of the plant, looking upwardly from the bottom of Figure 1, and illustrates the general arrangement of the fractional oil condensers, the vapor separators and the primary still.

General description of plant.

The complete topping plant illustrated in the accompanying drawings preferably 30 comprises eight vapor heat exchangers or fractional oil condensers, designated by the reference characters A, A', A², A³, A⁴, A⁵, A⁶ and A⁷, three vapor separators B, B' and B², a heat exchanger C, two heating coils 35 D and D', a primary still E, five re-run still and crock tower units F, F', F², F³ and F⁴, a condenser G, a number of conventional box condensers H and a number of coolers I, J, J' and K. When the plant is in operation crude oil is forced through a supply pipe 1 by means of a pump or other suitable means 2 and is passed through the fractional oil condensers wherein an exchange of heat takes place between the 40 crude oil and the hot vapors that are supplied to said fractional condensers from the vapor separators, resulting in condensation of some of the vapors and an increase in the temperature of the crude oil. The entire supply of crude oil delivered to the plant by the supply pipe 1 can either be passed in series through the fractional oil condensers and the heat exchanger C and then introduced into the first vapor separator B of the group of separators, or a portion of the crude oil can be passed through the fractional oil condensers, another portion can be passed through the heat exchanger and said 45 separate portions thereafter combined and introduced into the first vapor separator of the group. The vapor evolved in the first separator B is passed through a number of the fractional oil condensers and the liquid oil which collects in said first separator is forced through the heating coil D and then 50 into the second vapor separator B' of the group. The vapor evolved in the second separator is passed successively through a different group of the fractional oil condensers and thence through the group of 70 fractional oil condensers through which the vapor from the first separator B was passed. The liquid oil that collects in the second separator B' is forced through the second heating coil D' and then into the third vapor 75 separator B², and the vapor evolved in said third separator is passed successively through a few or all of the fractional oil condensers. The liquid oil that remains in the third separator B² after the vapors have 80 been driven off is conducted to the primary still E where the heating of the oil is completed, the vapors evolved in the primary still being conducted back to the third vapor 85 separator B² and subjected to a scrubbing action in said third separator. By handling the vapors in this manner the distillate can be divided roughly into 5% fractions which are grouped according to their boiling 90 points, the distillate of the highest boiling point being collected in the last fractional condenser A⁷ of the series and those of successively lower boiling points being brought 95 together in the other fractional condensers in the order of their remoteness to the last fractional condenser A⁷ of the series. If any of the lighter portions of the oil fail of vaporization in the first vapor separator B, they will be vaporized either in the second or third separator B' or B² and will 100 travel in the vapor state through the fractional oil condensers until they finally join portions of like volatility. Similarly, if any oil normally vaporizable at the temperature of the oil in the second vapor 105 separator B' should not be vaporized in the second separator, it will be vaporized either in the third vapor separator B² or in the primary still E and will then pass in the vapor state through the last fractional condensers of the series and finally join distillates of like volatility. Accordingly, the 110 distillates can be classified so precisely in accordance with their boiling points that the fractions in the various fractional condensers closely approach commercial requirements.

Such distillate as is required to be re-run is conducted from the fractional oil condensers to the re-run still and crock tower units F to F⁴, inclusive, and is passed through said re-run stills successively. Each of the re-run stills is so constructed that the distillate supplied to same will be caused to flow through the still in a tortuous path. The residuum from the primary still E is 120 preferably passed through heating tubes submerged in the distillate in the re-run stills so as to heat the distillate. The residuum from the last re-run still F⁴ of the 125

130

series is conducted to the heat exchanger C and the distillate from the last re-run still is conducted to the cooler J. The distillates which collect in the condensers G and H and in the coolers J and J' are finished products, except for treatment other than distillation.

Fractional oil condensers.

16 The fractional oil condensers are of the construction illustrated in Figure 3 of the drawings and each consists of a vertically-disposed, tubular-shaped member 3 provided at its lower end with a vapor inlet 4 and 15 at its upper end with a vapor outlet 5 so as to permit the vapor evolved in the vapor separators to be passed through said condensers. Vertically-disposed tubes 6 that are arranged inside of the member 3 and 20 combined with horizontally-disposed tube sheets 7 form an efficient means for heating the crude oil that is supplied to the condenser, the condenser being provided adjacent its upper end with an oil inlet pipe 25 8 arranged below the top tube sheet and an oil outlet 9 arranged above the bottom tube sheet. Baffles 10 that are arranged on the inner side of the tubular shell 3 of the condenser cause the oil that is admitted to the 30 condenser by the inlet pipe 8 to pass through the condenser in a tortuous path in contact with the vapor heated tubes 6, thereby enhancing the exchange of heat between the crude oil and the vapors. Preferably, a 35 perforated baffle plate 11 is arranged in the lower portion of the condenser in proximity to the vapor inlet 4 so as to throw down any liquid particles of oil which remain in the vapor, said baffle also operating to distribute 40 the vapor uniformly to the heating tubes 6. The condensed distillate is withdrawn from the lower end of the condenser through a liquid seal 12 which maintains a constant level of liquid in the condenser and prevents 45 the escape of vapor through the distillate outlet leading from the condenser.

When the plant is in operation the crude oil is forced through the oil supply pipe 1 and is passed successively through the 50 fractional condensers A to A⁷, inclusive, each of which is connected with the oil supply line 1 by an oil inlet pipe 8 and an oil outlet pipe 9. The oil supply line 1 is provided with controlling valves 13 arranged 55 between the oil inlets and outlets of the various fractional condensers, as shown in Figure 1, which valves 13 are normally closed but are capable of being manipulated independently of each other so as to enable the supply of crude oil to any particular fractional condenser to be reduced or cut off. The oil inlet and outlet pipes 8 and 9, respectively, of each fractional condenser are also equipped with controlling valves 14, 60 as shown in Figure 2, that are normally open

but which can be closed when it is desired to by-pass the crude oil around any particular condenser or cut said condenser out of service. During the passage of the crude oil through the condensers A to A⁷, inclusive, 70 an exchange of heat takes place between the oil and the vapors from the vapor separators B, B' and B², thereby causing a portion of the vapors to be condensed and the temperature of the crude oil to be increased 75 or raised.

After passing through the final condenser A⁷ of the series the crude oil returns to the supply line 1 and flows through said supply line to a pipe 15 which leads to the right, 80 looking at Figure 1, and connects with branch pipes 16 and 17 that lead to the sections 18 and 19, respectively, of the heat exchanger C. The heat exchanger C is preferably built in two sections so that one-half 85 of it may be cut out of service during cold weather or when it is necessary to repair same. The temperature of the crude oil is further raised in the heat exchanger C, and after passing through said heat exchanger, 90 enters a pipe 20 that leads to the first vapor separator B, as shown in Figure 1. In the foregoing description it has been assumed that all of the crude oil supplied by the pipe 1 first passes through the fractional oil 95 condensers A to A⁷, inclusive, and then through the heat exchanger C, but under some conditions of operating the plant it is desirable to split up the supply of crude oil 100 and cause part of the supply to pass through the fractional oil condensers and the remainder to pass through the heat exchanger C and thereafter combine the two separate streams of oil into a single stream that is 105 introduced into the first vapor separator B. In order that the plant may be operated in this manner, the portion of the oil supply pipe 1 that leads from the last fractional condenser A⁷ of the series is connected by 110 means of a pipe 21 with a pipe 20 that leads from the heat exchanger C to the first vapor separator B and the portion of the oil supply pipe 1 between the pump 2 and the first 115 fractional condenser A of the series is connected by means of a branch 22 with the pipe 15 that leads to the heat exchanger C, valves 23 and 24 being arranged in the pipes 21 and 15, respectively, on opposite sides of the point where the oil supply line 1 is connected to said pipes and the branch pipe 22 120 that leads from the oil supply line to the pipe 15 being provided with a controlling valve 25, as shown in Figure 1. If the valves 23 and 25 are closed and the valve 24 is open, the crude oil will flow in series 125 through the group of fractional oil condensers A to A⁷, inclusive and will then enter the heat exchanger C, but if the valve 24 is closed and the valves 23 and 25 are open partially or completely, half or any desired portion 130

of the oil will flow through the supply line 1 to the fractional condensers and thence through the pipe 21 that is tapped onto the pipe 20 that leads to the first vapor separator and the other half or portion of the oil will pass from the supply pipe 1 through the branch 22 directly to the heat exchanger C and thence from the heat exchanger through the pipe 20 to the first vapor separator. It will, of course, be obvious that the respective proportions of the oil which pass through the fractional condensers and through the heat exchangers can be varied by adjusting the valves 23 and 25. By constructing the apparatus in this manner the crude oil can be effectively used to cool or exert a cooling effect on the vapors supplied to the fractional condensers from the vapor separators B, B' and B².

20 *Vapor separators.*

The vapor separators B, B' and B² are of substantially the same construction and each consists of a vertically-disposed, tubular-shaped member equipped with a column of oppositely-inclined, cone-shaped baffles 26 and a spraying device 27 for introducing liquid oil into the upper portion of the separator at a point above the column of baffles therein, as shown in Figure 2 of the drawings. The baffles 26 are so constructed and arranged that the oil supplied by the device 27 will spread out in a thin film and travel downwardly the baffles and the vapor which rises from the downwardly flowing oil will travel upwardly through the separating chamber of the separator, out of the direct path of travel of the liquid oil and finally escape through a vapor outlet at the upper end of the separating chamber. If desired, horizontally-disposed baffles 28 can be arranged in the upper portion of the separating chamber of the separator in proximity to the vapor outlet so as to effect the separation of any solid particles of oil entrained with the vapor passing from the separator so as to eliminate the possibility of liquid oil escaping with the vapors and thus discoloring the distillate or rendering the distillate non-uniform with respect to its boiling point. During the passage of the oil through the fractional oil condensers or through the heat exchanger or through both the condensers and the heat exchanger, the temperature of the oil is raised above the boiling point of certain of its constituents. The vapor separators B, B' and B² are designed to release the vapor from the oil at atmospheric pressure. Consequently, when the oil is introduced into the first vapor separator B, a portion of it vaporizes and the vapors escape from the upper end of said separator through a pipe 29 that leads to a liquid trap 30, as shown in Figure 2. The liquid that collects in the trap 30

is conducted back to the upper end of the separating chamber of the separator B by means of a pipe 31 which is preferably provided with a loop 32 that forms a liquid seal which prevents vapor from passing back through the pipe 31. The vapors that enter the trap 30 escape therefrom through a pipe 33 that leads to the fractional condenser A², as shown in Figure 1, and the vapors which do not condense in the condenser A² are conducted through a pipe 34 into the succeeding condenser A' of the series, the vapors which pass through the condenser A without condensing being conducted through a pipe 35 to the first condenser A of the series. The most volatile vapors which pass through the condensers A², A' and A without condensing flow through a pipe 36 that leads from the fractional condenser A to the condenser G, as shown in Figure 1, the condenser G preferably being a box type condenser of conventional form.

The liquid oil which collects in the first vapor separator B is withdrawn therefrom by a pump 37 arranged in a line 38 leading from said separator, and is thereafter forced through the first heating coil D and thence into the second vapor separator B'. The second vapor separator B' is connected by means of a vapor outlet pipe 39 with a liquid trap 40 that is provided with a liquid return pipe that leads back to the upper portion of the separating chamber of the separator B', said liquid return pipe being similar to the liquid return pipe 31 of the separator B, previously referred to. Consequently, the portion of the oil supplied to the second separator B' which vaporizes at the temperature to which the oil is raised in the heating coil D, will pass by way of the pipe 39 to the trap 40. The vapors that enter the trap 40 escape from said trap through a pipe 41, shown in Figure 1, that leads to the fractional condenser A⁵. The vapors from the separator B' which pass through the condenser A⁵ without condensing are conducted by a pipe 42 to the fractional condenser A⁴, as shown in Figure 4, and those vapors which also fail of condensation in the condenser A⁴ are conducted by means of a pipe 43 to the fractional condenser A³. The vapor outlet 5 of the fractional condenser A³ communicates with the pipe 33 previously described through which the vapors escape from the first vapor separator B. Consequently, the vapors from the second separator B' which remain uncon- 115 densed in passing through the fractional condensers A⁵, A⁴ and A³ are combined with the vapors from the first vapor separator B, and advance with them into the fractional condensers A³, A² and A, A'.

The second vapor separator B' is connected at its lower end with a discharge line 44 in which a pump 45 is arranged, as

shown in Figure 1, said pump causing the liquid oil that collects in the second separator B' to be withdrawn therefrom and then forced through the second heating coil D' and thence into the third separator B² of the series. In passing through the coil D' the temperature of the oil is further raised so that additional vapors are generated in the third separator B² as the oil which is admitted to said third separator flows downwardly over the baffles of same, a greater portion of the volatile constituents having been removed by the time the oil reaches the lower end of the separating chamber of the third separator B². In view of the fact that the temperature of the oil is raised gradually in the fractional oil condensers, heat exchanger C and heating coils D and D', and the oil caused to spread out in a thin film on baffles in the vapor separators B, B' and B², the vapors are effectively separated without liability of causing the vapors to be superheated or cracked to any substantial degree.

40^a by a pipe 39^a, as shown in Figure 1. For convenience the liquid trap 40^a is mounted substantially at the level of the vapor separator B², and the fractional oil condensers, as shown in Figure 2. A liquid outlet pipe 70 32^a connects the bottom of the trap 40^a with the knock back pipe 46 leading to the primary still E. From the trap 40^a the vapors pass into a pipe 33^a which conducts said vapors into the bottom of the last fractional oil condenser A⁷ of the series where the heavier vapors are liquefied. The remainder of the vapors escape from the upper end of the condenser A⁷ into a pipe which conducts them into the fractional condenser A⁶. The vapor outlet 5 of the condenser A⁶ communicates with the pipe 41 so that the vapors from the third separator B² which are not condensed in either of the fractional condensers A⁷ and A⁶ are combined with the vapors from the second separator B', and in the event that they remain uncondensed, pass on through the condensers A⁵, A⁴, A³, A², A' and A and through the pipe 36 that leads to the box condenser G. 90

Primary still.

In order to drive off the last of the light vapors from the oil which collects in the third or last vapor separator B², said oil is conducted by a knock back pipe 46 to the primary still E. The primary still is of the construction illustrated in Figures 6 and 7 of the drawings and preferably consists of a horizontally-disposed, cylindrical-shaped member having steam pipes 47 arranged inside of same. At the upper end of said primary still is a dome 48 which communicates with a vapor pipe 49 that leads to the third vapor separator B² and enters the separating chamber of said separator at a point below the baffles therein, said dome being provided with vacuum and pressure relief valves 50 and 51, respectively. Consequently, the vapors generated in the still E will be introduced into the third vapor separator B² in such a way that said vapors will be somewhat scrubbed by the liquid oil escaping from the lowermost baffle of the column of baffles in the separator B², thereby insuring the removal of any particles of heavy oil that may be entrained with the vapor escaping from the primary still E. As shown in Figure 2, the third vapor separator B² is arranged at a higher level than the primary still E, the heating coils D and D' and first and second vapor separators so as to cause oil to flow by gravity through the oil inlet pipe 46 leading to the primary still. The fractional oil condensers A, A', A³, A⁴, A⁵, A⁶ and A⁷ are also elevated at substantially the same level as the separator B² so that distillates may be discharged from them by gravity.

out steam inasmuch as they have no vapor spaces. By means of the construction above described, however, I am able to obtain in an apparatus comprising alternate heating coils and vapor separators the advantages incident to the use of steam in distillation including lower distilling temperatures, purer distillates and the lifting effect of the steam in removing the last portions of light oil from the body of oil being distilled. The pumps 37 and 45 maintain a positive flow of the oil in the heating coils D and D', and thus insure the oil being heated uniformly in the coils. If a positive flow of oil were not maintained, portions of the oil might be vaporized in the coils and the vapors superheated and cracked, thereby causing carbon to become deposited in the coils. The pipe coils would thus become obstructed and eventually would become clogged to such an extent as to render further use of the apparatus impracticable until the coils had been taken apart and cleaned. The confinement of the oil in the heating coils D and D' retards the vaporization of the oil, and on account of the uniform heating of the oil in the coils resulting from positive and unobstructed flow of the oil through the coils, very little, if any, vaporization of the oil takes place in the coils. The various pumps that maintain a flow of the liquid oil through the apparatus are preferably driven at such speeds as to cause the oil to pass quite rapidly through the heat exchanger, through the fractional condensers and through the heating coils so as to give the plant a high capacity for

65 Vapors are conducted from the top of the third vapor separator B² to a liquid trap

The primary still E is heated by a furnace 130.

52 that is provided with a central chamber containing a fire box 53 and supplementary chambers 54 and 55 located on opposite sides of said central chamber and containing the 5 heating coils D and D' previously referred to. The still E is arranged over the central chamber of the furnace and the supplementary chambers 54 and 55 are connected by means of flues 56 and 57 with said central 10 chamber, thus causing the fire gases to pass from the central chamber beneath the still, and thence into the supplementary chambers 54 and 55. Valves 56^a and 57^a are arranged in the flues 56 and 57, respectively, so as to 15 regulate the flow of the furnace gases to the supplementary chambers, and thus enable the proportion and extent of the heat imparted by the furnace to the heating coils D and D' to be accurately controlled. Each 20 of the supplementary chambers above referred to is provided at its upper side and adjacent its rear end with a dome 58 that communicates with the flue that co-operates with said chamber, and the pipes that constitute the heating coils D and D' which are arranged in said chambers extend through the end walls of said chambers and are protected by guards 59 and 60 arranged over the return bend portions of said pipes, as 25 shown in Figure 9. The furnace gases escape from the chambers 54 and 55 through flues 61 leading from the bottoms of said chambers substantially in the vertical planes of the domes 58, and a horizontally-disposed 30 baffle plate 62 is arranged inside of each of said chambers so as to cause the furnace gases to flow first forwardly and then rearwardly in traveling through the chamber.

In the normal operation of the plant 40 above described the oil which does not vaporize in the still E, and which I will refer to as the residuum, is discharged from the still E through a pipe 63 leading from the rear end of the still and located at a sufficient height above the bottom of the still to normally maintain the still approximately half full of residuum. In order to enable 45 deposits of solid matter, such, for example, as carbon to be removed from the shell of the still from time to time means is provided for enabling the contents of the still to be discharged at intervals, and in the form of my invention illustrated the still is provided at its rear end and in line with its bottom 50 with an enlargement 64 equipped with a valve 65, shown in Figure 10, that is adapted to be opened when it is desired to discharge the contents of the still. The mechanism for actuating the valve 65 is illustrated in 55 Figure 10 and consists of a rod 66 connected to the valve 65 and secured to the piston 67 which operates in the cylinder 68. The discharge opening in the bottom of the still which the valve 65 normally closes is arranged in alignment with a draw-off pipe 66

69 on the underside of the still in which the valve rod 66 is guided. The heavy oil which collects at the bottom of the still is commonly termed "tar" and the valve 65 is of the type generally termed in the trade "tar 70 plug." Steam supply pipes 70 and 71 communicate with the interior of the cylinder 68 above and below the piston 67 in said cylinder, and adjacent the front end of the still a four-way valve 72 is provided for 75 controlling the admission and exhaust of steam to and from the cylinder 68 through the supply pipes 70 and 71 and a pressure pipe 72^a and exhaust pipe 72^b with which 80 said supply pipes co-operate.

It has been demonstrated by experience that fires in stills occur most frequently from a ruptured draw-off line and that in the event of a fire arising from such a cause it is always difficult and dangerous and often impossible to operate the conventional tar plugs with which stills are usually equipped. In the still above described the draw-off pipe 69 is separated from the combustion chamber of the furnace of the still 90 by the rear wall of the furnace so that the draw-off line is not liable to be ruptured, and even if it should become broken, the oil escaping therefrom would not be liable to be ignited. In the event of a fire, however, 95 the four-way steam valve 72 that governs the operation of the tar plug can be actuated easily and with perfect safety on account of its remoteness to the draw-off line which the tar plug controls. In order that 100 the tar plug or valve 65 may be manually operated the stem 66 of said valve is connected at its lower end to an operating handle 74 which is fulcrumed on a swinging 105 link 75, as shown in Figure 10, the movement of said handle being limited by stationary stops 75^a arranged above and below the handle.

Re-run still and crock tower units.

As previously stated, my improved plant 110 comprises five re-run stills F to F', inclusive, that are combined with the fractional oil condensers in such a manner that such 115 distillate as requires further treatment can be passed through said re-run stills. The re-run still and crock tower units are of the same design and each consists of a horizontally-disposed, cylindrical-shaped member 120 76 whose interior is divided by means of longitudinally-disposed partitions 77 into a number of oil compartments in the lower portion of the still and a vapor space in the upper portion of the still common to all 125 of said oil compartments, the partitions 77 being provided with openings 78 arranged so that the distillate which is supplied to one end of the still through an oil inlet pipe 79 will flow through the still in a tortuous 130 path, and finally escape from the still 130

through an outlet pipe 79^a located at the same end of the still through which the oil is admitted. Longitudinally-disposed heating tubes 80 that are submerged in the oil in the various oil compartments of the still are combined with headers 81 and 82 at opposite ends of the still in such a manner that a heating medium consisting preferably of the residuum from the primary still E can be admitted to the header 81 at one end of the still through an inlet pipe 83, and after passing through the various oil compartments of the still, will escape from the opposite side of said header through an outlet pipe 84, as shown in Figure 11. Perforated steam pipes 85 are preferably arranged in the still in the bottom of each of the longitudinal compartments of the still through which the distillate flows so as to agitate the distillate and tend to lift over the vapors, thereby reducing the temperature required for distillation, the perforated steam pipes 85 of each re-run still being connected with a header 85^a, as shown in Figure 5, which headers communicate at one end with a steam supply pipe 85^b and at the other end with an exhaust pipe 85^c. In the normal operation of the apparatus the residuum is conducted from the primary still E to the re-run stills F to F⁴, inclusive, through a pipe 86, shown in Figures 2 and 4, but if desired, the residuum discharged from the bottom of the primary still through the discharge opening controlled by the tar plug 65 may be conducted to the re-run stills through a pipe 87, shown in Figure 4, that connects the draw-off pipe of the primary still with the pipe 83. The draw-off pipe is also provided with a discharge means (not shown) separate from the pipe 86 in order that the contents of the primary still may be discharged without passing through the re-run stills. As shown in Figure 5, the pipe 86 communicates with a pipe 88 that extends along the line of re-run stills and which is connected to the residuum inlets 83 and outlets 84 of the stills by pipes 83^a and 84^a, respectively. The pipes 83^a and 84^a are provided with suitable control valves and valves 89 are located in the pipe 88 between the inlet pipe 83^a and outlet pipe 84^a of each still. Normally, the valves 89 are closed and the valves in the residuum inlet and outlet pipes are open. If desired, however, any of the re-run stills may be cut off from the residuum supply pipe 88 by closing the valves in the residuum inlet and outlet pipes of said still and opening the appropriate valve 89 in the residuum supply pipe. The residuum from the final re-run still F⁴ of the series enters a pipe 90 and is conducted through said pipe to the heat exchanger C, as shown in Figure 1.

Each of the re-run stills just described is provided with a crock tower 91 through

which vapors pass from the still, and said crock towers may, if desired, be provided with safety vacuum and pressure relief valves. As shown in Figure 11, each of the crock towers 91 consists of a vertically-disposed, tubular-shaped member mounted on the still with which it co-operates adjacent to the end of the still through which the inlets and outlets for the distillate and for the residuum are located and provided at its lower end with a skeleton-like supporting structure 92 on which crock tile 93 are arranged so as to form a vertical column of tile. The crock tile may be of any preferred construction, so long as they are of such design as to provide relatively large contact surfaces, and at the upper end of the tower a multiple-arm spraying device 94 is arranged so as to introduce oil into the upper end portion of the crock tower above the tile therein. A perforated baffle 95 that is arranged in the upper portion of the crock tower above the spraying device 94 prevents liquid oil from being carried out of the crock tower with the vapor that escapes through the vapor outlet 96 that leads from the upper end of the crock tower to one of the condensers H. The liquid oil which escapes from the lower end of the crock tower collects in a funnel-shaped device 97 inside of the still beneath the lower end of the crock tower and is conducted from said funnel-shaped device through a pipe 98 back to the oil inlet of the still of which the crock tower forms a part. Accordingly, the oil which is condensed in the crock tower will be returned to the re-run still with which the crock tower co-operates and oil which first enters the re-run still of each unit by way of the crock tower forming part of the unit will be raised to the temperature of the rest of the oil in the still before it reaches the oil outlet 79^a through which the unvaporized portion of the oil escapes from the still. I make no claim herein to the re-run still and crock tower units above described, as they form the subject-matter of my pending application for patent Serial No. 525,167, filed December 27, 1921.

Piping system of the plant.

The particular arrangement of the various pipes and valves that make up the piping system which connects the various elements of the plant together is immaterial, so far as my broad idea is concerned. In the apparatus herein illustrated pipes 100 and 101 which supply the distillate to the spraying devices 94 in the crock towers and to the oil inlets 79 of the re-run stills are connected to pipe manifolds 102 that extend transversely of the re-run stills, as shown in Figure 4, and to which the distillate is supplied from the fractional condensers,

the flow of the distillate through the pipes 101 being controlled by valves 103, as shown in Figure 2, and the amount of distillate admitted to the crock towers 91 being regulated by valves 104. The quality of the vapor evolved in any crock tower can be varied as desired, simply by changing the amount of distillate introduced into the crock tower.

10 Although the distillates from the fractional oil condensers are still warm when they enter the re-run stills and crock towers, the portion of the distillate which is discharged into the crock towers causes the upper portions of the towers to be relatively cool as compared with the lower portions of the towers. Consequently, a portion of the vapors will be condensed as they rise in the crock towers. The condensed oil, however, 20 as it flows downwardly in the crock towers meets the hot vapors rising from the still and may be again vaporized. In this way, the crock towers act continuously to re-boil the oil which results in effecting a maximum separation of the distillate within the required boiling point range.

The oil outlet 79^a of the last re-run still F⁴ of the series connects with a pipe 105, by which the bottom oil from the still F⁴ is combined with the oil entering the re-run still F³ by the pipe 101. In a like manner, the bottom oil from each of the re-run stills is conducted to the next adjacent still of the series counting from the re-run still F⁴. The oil which is not vaporized in any of the series of stills is delivered from the plant by a pipe 106 and may be led to a cooler K, as shown in Figure 1. It will be noted from the foregoing that the flow of bottom oil in the re-run stills is from the last still F⁴ to the first still F, whereas, the flow of residuum in said re-run stills is from the first still F to the last still F⁴ of the series.

45 The apparatus is preferably equipped with coolers for cooling the lighter low boiling oil fractions which do not require to be re-run. Two such coolers J and J' are indicated diagrammatically in Figure 1 between the condenser G and the upper one of the box condensers H. The coolers J and J' are connected to the manifold piping 102 by pipes 107 and 108, respectively.

The distillates from the fractional oil condensers A to A⁵, inclusive, flow by gravity to the manifold piping 102 along pipes 109, 110, 111, 112, 113, 114, 115, and 116, respectively, as shown in Figure 4. The streams of distillate from the fractional oil condensers may be sampled, and the manifold piping 102 is so arranged and controlled by valves that the distillate from any of the fractional condensers can be directed to the proper re-run still for re-distillation. Manifestly, the arrangement of the pipes and

valves in the manifold 102 may vary widely. One arrangement which will accomplish the desired result is illustrated diagrammatically in Figure 1, wherein the pipe 116 leading from the last fractional oil condenser A⁵ connects with a pipe 117, in which are two valves 118 and 119. The valve 118 is normally closed and the valve 119 normally open so as to cause the distillate to be delivered to the re-run still F. The pipes 115, 114 and 113 associated with the fractional oil condensers A⁶, A⁵ and A⁴ are connected with pipes 120, 121 and 122 arranged to deliver distillate to the re-run stills F', F² and F³, respectively. The pipe 120 is provided with a valve 123 disposed in the path of flow of distillate from the pipe 115 to the re-run still F', and the pipes 121 and 122 are each equipped with valves on opposite sides of the point of connection of the pipes 114 and 113 with them. These valves are designated in Figure 1 by the numerals 124, 125, 126, and 127. Short pipes 128, 129 and 130 connect the pipes 117, 120, 121 and 122 intermediate between the valves 118, 124 and 125.

The pipes 112 and 111 leading from the fractional oil condensers A³ and A² are connected with pipes 131 and 132, respectively. The pipe 131 is provided with a valve 133, and a pipe 134 joins the pipes 122 and 131 intermediate between the valves 125 and 133. The pipe 132 is arranged to deliver distillate to the re-run still F⁴, and is provided between the pipe 111 and the re-run still F⁴ with a valve 135. A pipe 136 joins the pipe 132 to the pipe 131, and a valve 137 is located in the pipe 132 between the pipes 111 and 131. A short pipe 138 controlled by a valve 139 connects the pipe 131 with the pipe 122 intermediate between the valve 127 and the re-run still F³. On the opposite side of the valve 127 the pipe 122 is connected to the pipe 121 by a short pipe 140 which is controlled by a valve 141. The pipe 140 joins the pipe 121 between the valve 126 and the re-run still F². In a like manner, another pipe 142 having a valve 143 unites the pipes 121 and 120 between the valves 126 and 123. The valves 118, 124, 125, 133, 139, 141 and 143 are normally closed, and the valves 119, 123, 126, 127, 137 and 135 are normally open.

With the arrangement of pipes and valves above described the flow of distillate from the fractional oil condenser A⁶ may be diverted from the re-run still F to the still F' by closing the valve 119 and opening the valve 118; the flow of distillate from the fractional oil condenser A⁶ may be diverted from the re-run still F' to the still F² by closing the valve 123 and opening the valve 124; the flow of distillate from the fractional oil condenser A⁵ may be diverted from the re-run still F² to the still F³ by closing the valve 127 and opening the valve 139.

closing the valve 126 and opening the valve 125; and the flow of distillate from the fractional oil condenser A⁴ may be diverted from the re-run still F³ to the still F⁴ by closing the valve 127 and opening the valve 137. The distillates from the fractional oil condensers A³ and A² normally combine and flow into the re-run still F³. If desired, however, the distillate from the fractional condenser A³ may be combined with that from the fractional oil condenser A⁴ and caused to flow into the re-run still F³ by closing the valve 137 and opening the valve 139. Moreover, assuming that the valve 137 is in its normally open position, if the valve 135 is closed and the valve 139 opened, the distillate from both of the fractional oil condensers A³ and A² will be delivered into the re-run still F³. It may be desired under some conditions of operation of the plant to divert the distillate from the fractional oil condenser A⁴ into the re-run still F² while the distillate from either or both of the fractional oil condensers A³ and A² is being fed into the re-run still F³. This may be effected by closing the valve 127 and opening the valve 141. In a like manner, while the distillate from fractional oil condenser A⁴ is being directed to re-run still F², the distillate from the fractional oil condenser A⁵ may be diverted from the re-run still F² to the still F' by closing the valve 126 and opening the valve 143. It will also be apparent that by closing the valve 123 and opening the valve 118, the distillate from the fractional oil condenser A⁶ may be combined with that from the fractional oil condenser A⁷ and caused to flow into the re-run still F.

As previously indicated, it is believed that the distillates from the fractional oil condensers A and A' will not ordinarily require to be re-run. In order that they may be re-run, if desired, however, the pipe 108 is connected to the pipe 122 by a short pipe 144 controlled by a valve 145, and the pipe 107 is joined to the pipe 132 by a pipe 144^a controlled by a valve 145^a. The pipe 108 has a valve 147 between the pipe 144 and the cooler J', and the pipe 107 has a similarly located valve 148 between the pipe 144^a and the cooler J. A pipe 149 controlled by a valve 149^a connects the pipe 144^a to the pipe 144 between the valve 145 and the pipe 108. When the valves 147 and 148 are closed and the valves 145 and 145^a are open, the distillate from the condensers A and A' will be delivered to the re-run stills F³ and F⁴, respectively. By opening the valve 149^a and closing the valves 145 and 147, the distillate from the condenser A' may be caused to flow into the re-run still F⁴.

It is believed that it will be evident without further exposition that the illustrated arrangement of pipes and valves en-

ables the distillate from any of the condensers A to A' to be delivered either by itself or in combination with distillate from other condensers into any of the re-run stills or coolers where it may be desirable to deliver it. Inasmuch as it is believed that the distillate from the fractional oil condenser A' contains sufficient light oil to justify re-running it, such distillate is, in the illustrated apparatus, delivered to the re-run stills. If, however, it should prove to be uneconomical to re-run the distillate from the condenser A', it may be by-passed around the re-run stills to coolers and storage.

In the use of the apparatus the distillation of the oil is carried on continuously, and the final distillates are substantially finished products requiring no further distillation. The crock towers cause the finished products to be of definite gravities and boiling points, and the use of steam in the re-run still supplements the action of the crock towers in causing the finished products to be of good quality and color.

Heat exchanger.

The heat exchanger C is preferably of the construction illustrated in Figures 13 to 17, inclusive, and is composed of two sections 18 and 19, each of which comprises a set of outer tubes 150 and a group of small tubes arranged in each of said outer tubes. Preferably, seven small tubes 151 are located in each of the outer tubes 150 and said outer tubes are arranged in superimposed batteries of three disposed in substantially parallel horizontal planes. Adjacent tubes of the same and adjacent batteries are connected by T-shaped couplings 152 and elbows 152^a, so as to permit the liquid to flow from one end of the heat exchanger to the other. The inner tubes 151 extend through the tubes 150 and couplings 152 and the opposite end portions of said inner tubes are positioned in openings in plates 153 clamped between the couplings 152 and rings 154 threaded on the elbows 152^a, shown in Figure 15. The ends of the inner tubes 151 are preferably reduced where they extend into the openings of the plate 153, and the openings in said plate are enlarged on the outer side of the plate so as to receive glands 155 which are held pressed tightly against the tubes 151 by threaded ferrules 155^a. The residuum is introduced into the heat exchanger, to an inlet 156 on one of the bottom tubes of the heat exchanger and is conducted out of the heat exchanger through an outlet 157 on one of the upper tubes of the heat exchanger. The crude oil is introduced into the heat exchanger through an inlet 158 in the end of the coupling that contains the residuum outlet 157, and after passing

through the heat exchanger, escapes through an oil outlet 159 formed preferably in the coupling which contains the residuum inlet 156. It will thus be seen that the residuum flows along the tubes 150 of the heat exchanger outside of the inner tubes 151, and that the crude oil flows through the inner tubes 156 in an opposite direction to the direction of flow of the residuum through the heat exchanger, the residuum being conducted away from the heat exchanger through pipes 160 and 161 that lead to a cooler I. Preferably, a group of small tubes 151 in each of the outer tubes 150 are supported and held in spaced relation by spiders 162, as shown in Figure 17, each of said spiders being provided with a central opening to receive the center tube of the group and other openings which permit the other tubes of the group to be arranged in a circle around the central tube. As shown in Figure 18, the tubes 151 are held in place in the spiders 162 by metal straps 164 disposed on each side of the spider.

Operation of plant.

As previously stated, crude oil is supplied to the plant through the pipe 1 and is passed through fractional oil condensers and heat exchanger, or part through the fractional condensers and part through the heat exchanger, and thereafter introduced into the first vapor separator of the group of three vapor separators. The most volatile constituents of the oil vaporize in the first separator and pass off to be condensed and the liquid oil which collects in the first vapor separator is forced through the first heating coil and then into the second vapor separator. The vapors evolved in the second separator pass off to the condensers and the liquid oil that collects in the second separator is pumped through the second heating coil to the third vapor separator. The crude oil then flows into the primary still where the heating of the oil is completed. The vapors evolved in the first vapor separator are passed through the group of three of the fractional oil condensers, the vapors evolved in the second vapor separator are passed through an independent group of the fractional condensers and also through the group through which the vapors from the first vapor separator were passed and the vapors from the still are conducted to the third separator, the vapors evolved in the third separator being conducted into the last fractional condenser of the series and then passed successively through the other fractional condensers of the series in a direction opposite to the direction of flow of the crude oil through said fractional condensers. The distillates in the fractional condensers are conducted to the re-run still and crock tower units and the vapors arising from the redistillation of the distillates in the re-run stills are conducted through pipes to the box condensers H. The bottom oil in the re-run stills flows through said stills successively from the last still F* to the first still F of the series and finally escapes through the discharge pipe 106 that leads to the cooler K. The residuum, after successively passing through the re-run stills from the first still F to the last still F* of the series, is conducted through the heat exchanger C, and thence passes into the cooler I. The distillates which collect in the condensers G and H and in the coolers J and J' are finished products, except for treatment other than distillation.

Having thus described my invention, what I claim as new and desire to secure by Letters Patent is:

1. A method of distilling oil which comprises heating oil in successive stages, allowing vaporization to take place between said stages, maintaining the vapors from each heating stage separated from the vapors resulting from the preceding heating stages, and while so separated condensing a portion of said vapors from each stage into fractions of varying volatility, then combining the remaining uncondensed vapors from all the stages, condensing the combined vapors conducting heavier of said fractions of varying volatility for re-distillation to separate re-run stills of a series, re-distilling said heavier fractions in said re-run stills, and adding the residue from each of said re-run stills to the next in series.

2. A method of distilling oil which comprises continuously subjecting oil to primary distillation in a plurality of stages, combining and collecting together into separate fractions vapors of similar boiling points evolved in said stages, separately condensing each of said fractions, conducting heavier of said fractions for re-distillation to separate re-run stills of a series, re-distilling said heavier fractions in said re-run stills, and adding the residue from each of said re-run stills to the next in series.

3. A method of distilling oil, characterized by heating oil to vaporize certain of its constituents, condensing vapors evolved by said heating by exchange of heat between said vapors and incoming crude oil, collecting the remaining vapors in groups in accordance with their boiling points, re-distilling distillates condensed by said exchange of heat by heat contained in the oil remaining unvaporized after said heating operation, and finally passing said unvaporized oil into heat exchange relation with incoming crude oil.

4. A method of distilling oil charac-

- terized by intermittently heating oil that is confined under a slight pressure, relieving said pressure between the heating operations to cause the volatile parts of same to 5 separate from the liquid oil, condensing vapors into fractions of varying volatility, combining uncondensed vapors of similar boiling points and condensing them, conducting heavier of said fractions of varying 10 volatility for re-distillation to separate re-run stills of a series, re-distilling said heavier fractions in said re-run stills, and adding the residue from each of said re-run stills to the next in series.
- 15 5. A method of continuously distilling oil which comprises subjecting oil to repeated heating operations of gradually increasing temperatures, spreading out the oil in a film after each heating operation to allow part 20 of the oil to separate in the form of vapor, passing vapors resulting from the final heating operation into contact with unvaporized oil from the preceding heating operation whereby said vapors are scrubbed by liquid 25 oil, condensing portions of the vapors resulting from each of the heating operations into fractions of varying volatility, combining uncondensed vapors of similar boiling points remaining after fractional condensation, and condensing said combined vapors.
- 30 6. A method of distilling oil, characterized by subjecting oil to repeated vaporizing operations, combining fractions of similar boiling point and condensing them to form 35 primary distillates of varying volatility, and continuously redistilling the primary distillates as separate bodies, the residue from the bodies of lighter distillates being added in series to the bodies of heavier distillates.
- 40 7. A method of distilling oil, characterized by heating oil in stages, spreading the oil into films between the heating stages to separate the vaporizable parts thereof in accordance with the temperatures imparted to 45 it in the heating stages, combining fractions of similar boiling point and condensing the different fractions separately into primary distillates, and continuously re-distilling the primary distillates in separate bodies, the residue from the bodies of lighter distillates being added in series to the bodies of heavier distillates, and heat for the redistillation of the primary distillates being furnished by the residue from the said heating of the oil.
- 50 8. A method of continuously distilling oil, characterized by subjecting oil to successive heating operations, separating the vapors after each heating operation, combining vapors of similar boiling point and fractionally condensing them into primary distillates, continuously re-distilling the primary distillates in separate bodies, causing the residue from the bodies of lighter distillates to flow in series into the heavier distillates, and supplying heat for re-distilling said bodies of
- primary distillate by flow of the residue of the successive heating of the oil in heat conducting relation with the bodies of primary distillates and counter-current to the residue of said bodies.
- 70 9. A method of continuously distilling oil which comprises heating oil in successive primary stages, combining vapors evolved in each stage with vapors of similar boiling point evolved in the other stages, condensing said vapors into fractions of varying volatility, re-distilling said fractions in a series of separate bodies, and continuously adding to certain of said bodies an accretion of fresh distillate from said primary heating and condensing stages and a residue from another body of distillate of said series from which oil of lower gravity is being distilled.
- 75 10. A method of continuously distilling oil which comprises heating oil in successive stages, condensing vapors formed in each stage into fractions of varying volatility, combining remaining uncondensed vapors evolved in each stage with vapors of similar boiling point evolved in the other stages, condensing said combined vapors into fractions of varying volatility, continuously re-distilling the heavier of said fractions in a series of separate bodies, heating said bodies by interchange of heat with the residue from the successive heating in stages of the oil, and aiding the re-distillation in said bodies by introduction of steam thereinto.
- 80 11. An oil distilling apparatus comprising a heating coil, a vapor separator connected to said heating coil and adapted to receive oil therefrom, a series of condensers, means for passing vapors from said separator through a plurality of condensers of said series, a second heating coil, means for conducting unvaporized oil from said separator to said second heating coil, a second separator connected to said second heating coil and adapted to receive oil therefrom, and means for conducting vapors from said second separator through a plurality of condensers in the series separate and distinct from the condensers through which the vapors from the first vaporizer were passed and thereafter through the first mentioned plurality of condensers.
- 85 12. An oil distilling apparatus comprising a series of heating coils and vapor separators interposed between said coils, a series of condensers, means for conducting crude oil through the condensers and in counter-current to the flow of vapors therethrough and thence to the first heating coil in the series, a series of stills for re-distilling distillates from said condensers, connections from said condensers to said series of stills, means for conducting distillates through said series of stills, and means for conducting unvaporized oil from the last of the series of heating coils to and through said
- 90 95 100 105 110 115 120 125 130

stills in countercurrent to the flow of distillate therethrough.

13. An oil distilling apparatus, comprising a series of heating coils, a vapor separator connected to each of the heating coils including the final coil, a series of condensers, means for delivering vapors from said separators to said condensers, a still, means for conducting to the still the oil remaining unvaporized after passing through the heating coils and separators, and means for conducting the vapors given off from the still to the vapor separator connected to the final heating coil.

14. An oil distilling apparatus comprising a heating coil, a vapor separator, means for conducting oil from said heating coil to the upper portion of said separator, inverted cone shaped baffles within said separator and below the point of communication of said conducting means with said separator, an upright cone shaped baffle within each of said inverted cone shaped baffles, a plurality of condensers arranged in series, means for delivering vapors from said separator to

said condensers, a still, means for conducting unvaporized oil from said separator to said still, and means for conducting vapors from said still to the lower portion of said separator and below the baffles therein. 30

15. An oil distilling apparatus for continuously distilling crude oil into finished products, comprising means for heating oil to vaporize certain of its constituents, a series of condensers, means for delivering 35 vapors evolved in said heating means to said condensers, means for refining condensates from the condensers including a series of re-run stills, crock towers on the re-run stills, means for conducting condensates 40 from the condensers to the re-run stills, means for conducting condensates from the condensers to the crock towers to scrub the vapors from the re-run stills so as to allow only vapors of definite gravity to pass from 45 them, and means for introducing steam into the re-run stills to improve the color of the vapors.

JAMES M. WADSWORTH.
